PICKER STICK GUIDE

Edward C. Nichols, Upton, Mass., assignor to
Draper Corporation, Hopedale, Mass., a corpora-
tion of Maine

Application February 7, 1944, Serial No. 521,363

5 Claims. (Cl. 139—255)

The present invention relates generally to automatic looms and, as illustrated herein, relates more particularly to improvements in chutes for ejected filling carriers for such looms.

During the filling replenishing operation of automatic looms, the ejected filling carrier may fall tip first into the picker stick slot and will lodge therein. During the first pick after replenishing, the picker stick will strike the improperly positioned filling carrier and severe and serious damage may be caused to the loom.

One object of the present invention is to provide means which will prevent an ejected filling carrier or bobbin from falling into the picker stick slot. To this end, the loom is provided with a filling carrier chute or guide which will normally cause the tip end of the ejected filling carrier to fall away from the picker stick slot and hence be prevented from falling therein. By this construction, dangerous and damaging contact of the picker stick with the ejected filling carrier is prevented.

With the above and other objects and features in view, the invention will now be described with particular reference to the accompanying drawings which illustrate a preferred embodiment of the invention and in which:

Fig. 1 is a view in front elevation of the end of a lay having one form of the invention applied thereto;

Fig. 2 is a view, partly in section, taken along the line II—II of Fig. 1; and

Fig. 3 is a view, partly in section, taken along the line III—III of Fig. 2.

The illustrated embodiment of the invention is shown as applied to an automatic loom wherein the filling replenishing mechanism operates when the filling on the old filling carrier in the operating shuttle is broken or exhausted to eject the old filling carrier by inserting a new filling carrier in the shuttle. The shuttle box in which the filling replenishing operation takes place is usually at the right hand end of the lay opposite to the replenishing mechanism. This replenishing mechanism may be of any usual construction and includes a rotary magazine (not shown) for holding a supply of filling carriers and mechanism including a transerrer 10 which is arranged to be reciprocated into engagement with a new filling carrier 12 and to eject an old filling carrier 14 on which the filling is either broken or substantially exhausted.

The lay 16 is provided with a shuttle box (not shown) in which a shuttle 18 is received. The shuttle 18 is provided with a spring 20 for re-

leasably supporting the bobbin or filling carrier 12 in position therein. The lay 16 is provided with a bottom plate 22 which serves as a shuttle race and rests directly on top of the lay

16. The plate 22 is cut away to provide a slot 24 in which the picker stick moves and through which the ejected filling carrier falls during the replenishing operation. The lay 16 is cut away below and forwardly of the slot 24 as is usual in looms of this type.

The shuttle 18 is picked by a picker stick (not shown) which travels in a picker stick slot 26 which, as shown in Fig. 2, is below the lay 16. A check strap 28 is provided for checking the picker stick. The check strap 28 is normally received between stationary fingers 30 and an adjustable finger 32. The fingers 30 project downwardly and the finger 32 is staggered relatively thereto and thus exerts a retarding effect on the check strap 28 as the picker stick moves the strap through the fingers as the picker stick approaches the inner or outer limits of its movement.

The transerrer 10 is shown in Figs. 1 and 2, at the conclusion of the filling replenishing operation. The ejected bobbin 14 has been forced out of the spring jaws 20 in such a manner that it strikes the chute 34 which deflects the bobbin 14 in a bobbin box or other receptacle provided for the purpose. The chute 34 is secured to the outer end of the lay in usual manner. The construction and operation of the parts so far described are well known in the art and need not be further described herein.

As before stated, the ejected filling carrier does not always fall in its intended and usual manner so as to be deflected into the receiving can by the chute. The filling carrier sometimes falls in such manner that it enters tip first into the picker stick slot. The reason or cause for this unusual action is not always apparent but when it is remembered that the filling carrier is gripped only at its butt end and that the filling carrier is ejected at a relatively high rate of speed and with varying amounts of filling thereon, it is apparent that an occasional filling carrier may be ejected so that the tip thereof falls into the picker stick slot. The slot is of substantially less width than the diameter of the butt and hence the filling carrier will remain in the slot and will be struck by the picker stick. Only very rarely does this condition arise but when the tip of the filling carrier falls into the picker stick slot substantial damage to the loom often results.

55 The present invention provides means which

engages the ejected filling carrier and prevents the tip from falling into the picker stick slot. The chute 34 referred to above is formed of two parts, a picker stick guide 36 and a sheet metal chute member 38. The picker stick guide 36 is preferably formed of cast iron and of which the depending friction fingers 30 form an integral part. The inner end of the picker stick guide has a forwardly and downwardly inclined portion 40 to which the chute member 38 is secured by suitable screws 42. The inner end portion of the picker stick guide is held in position by a cap screw 44 which is threaded into a rearwardly projecting boss 46 as is usual in constructions of this type.

The downwardly extending portion 40 is inclined inwardly and rearwardly to such an extent that the tip of the ejected filling carrier will be projected forwardly. The degree of inclination of the portion 40 is illustrated most clearly in Fig. 3 where the sheet metal chute plate 38 is shown in section as inclined inwardly and rearwardly toward the lay 16. By this construction, the shank of the ejected filling carrier will engage the outer edge of the plate 38 and the butt of the filling carrier will engage the surface of the plate a substantial distance inwardly of the outer edge thereof. As a result, the tip of the filling carrier is tilted forwardly away from the picker stick slot and danger of the filling carrier entering said slot is consequently eliminated.

The metal plate or sheet 38 extends upwardly above the upper edge of the portion 40 and terminates closely adjacent to the top surface of the lay 16. The sheet 38 is of such thickness that it may be sprung or otherwise shaped to fit closely against the wall of the picker slot 26. As illustrated, the lay 16 (Fig. 2) is cut away or bevelled slightly to provide a bearing for the upper end portion of the sheet 38. The inner edge of the sheet 38 is provided with an upturned flange 48 which prevents excessive and undesired inward movement of the filling carriers as they are being ejected and deflected into the receiving can.

By the use of the above construction the ejected bobbin or filling carrier will strike against the plate 38 and will not engage the wooden lay 16. Thus excessive wear on the lay is prevented and substantially uniform deflection of the ejected filling carriers is insured. The chute member or plate 38 may readily and conveniently be replaced when it becomes worn.

Having thus described my invention what I claim as new and desire to secure by Letters Patent of the United States is:

1. An automatic loom having a lay, a shuttle box on said lay having a slot in its bottom through which a filling carrier may be ejected, a picker stick guide fixed to said lay below said shuttle box, and forming with said lay a slot for a picker stick, means for transferring a filling carrier to said shuttle and ejecting a filling carrier on which the filling is substantially exhausted, and means supported on said picker stick guide and having an inwardly and rearwardly inclined surface against which the filling carrier is ejected, said surface being so arranged that the outer edge portion of said surface will engage the shank of said ejected filling carrier intermediate of its ends and the butt of said filling carrier to deflect the tip of said filling carrier away from said picker stick slot.

2. In an automatic filling replenishing loom, a

lay, a shuttle box on said lay having a slot in its bottom surface through which a filling carrier may be ejected, a shuttle in said shuttle box, a picker stick guide mounted on said lay below said shuttle box to provide a picker stick slot between said lay and said guide, means for transferring a filling carrier into said shuttle and ejecting a filling carrier on which the filling is substantially exhausted, and means carried by the picker stick guide and having a surface inclined inwardly and rearwardly and arranged with its outer edge portion to engage the shank of said filling carrier to deflect said tip away from said picker stick slot.

15. 3. In an automatic filling replenishing loom, a lay, a shuttle box on said lay having a slot in its bottom through which a filling carrier may be ejected, a shuttle in said shuttle box, a picker stick guide mounted on said lay below said shuttle box to provide a picker stick slot between said lay and said guide, means for transferring a filling carrier into said shuttle and ejecting a filling carrier on which the filling is substantially exhausted, and means on said picker stick guide having a surface arranged to be engaged by said ejected filling carrier, said surface being inclined downwardly and forwardly away from said shuttle box and also having a portion thereof inclined inwardly and rearwardly to provide a portion for engaging the shank of said ejected filling carrier and to deflect the tip of said carrier upwardly and forwardly away from said picker stick slot.

4. An automatic loom having a lay, a shuttle box on said lay having a slot in its bottom through which a filling carrier may be ejected, a picker stick guide fixed to said lay below said shuttle box, and forming with said lay a slot for a picker stick, means for transferring a filling carrier to said shuttle and ejecting a filling carrier on which the filling is substantially exhausted, said picker stick guide having an inner downwardly projecting portion having an upper surface inclined generally downwardly and forwardly and also inwardly and rearwardly to provide a portion arranged to be engaged by the shank of the ejected filling carrier to deflect the tip of the filling carrier away from the picker stick guide, and means fixed to said surface and projecting upwardly therefrom and in contact with the vertical surface of the lay below said shuttle box slot, said means being effective to prevent wear on the wooden lay end and to provide a smooth continuous surface for deflecting the ejected filling carrier.

55. 5. An automatic loom having a lay, a shuttle box on said lay having a slot in its bottom through which a filling carrier may be ejected, a picker stick guide fixed to the lay below said shuttle box and spaced therefrom to provide a picker stick slot, means for transferring a filling carrier to said shuttle and ejecting a filling carrier on which the filling is substantially exhausted, said picker stick guide having an inner downwardly projecting end portion having an upper surface inclined downwardly and forwardly and also inwardly and rearwardly, and a sheet metal member secured to said surface and having an upwardly extending portion, said portion being forced against the vertical surface of the lay beneath the inner end portion of the slot in the shuttle box thereby forming an even continuous surface against which said filling carrier may be ejected.

EDWARD C. NICHOLS.
